[57] ABSTRACT

Apparatus for abrasively trimming resistors and other electrical elements is provided with means for manually interrupting the trim cycle in order to trim more precisely. Control components, including a solenoid valve and a gang switch operate to divert pressurized air from the air motor of the traversing mechanism and to stop the abrasive stream when the switch button is depressed. Trimming resumes when the switch button is released. Repeated depression of the switch button during the trim cycle enables the operator to trim precisely. A foot switch is also depressed until the end of the trim cycle.

ABRADING APPARATUS

SUMMARY OF THE INVENTION

This invention relates to abrading apparatus, more particularly to apparatus for trimming electrical components such as resistors to the desired electrical value with a jet of airborne abrasive powder or particles.

The basic abrading apparatus comprises an air supply, a powder reservoir with vibrator and mixing chamber, and a supply conduit fitted with an appropriate nozzle. Under pulsation from the vibrator abrasive powder trickles into the pressurized airstream, the amount depending on the amplitude of vibration. A rheostat may be employed to regulate the amplitude of vibration and, consequently, the intensity of abrasive cutting action.

To the basic abrading apparatus is added a control system, also a controlled drive with stop-action for the nozzles. It is contemplated that a work-piece such as a resistor will be placed in a holder. Thereafter, on signal the machine starts the abrasive jet flow and nozzle motion, and stops the entire proceedings when predetermined resistance values have been reached.

According to the present invention, provision is made to permit the operator of an abrasive trimming device to interrupt the trimming operation optionally without returning the nozzle to the original starting position. This is accomplished by depressing a push button while keeping a foot switch depressed. By repeatedly depressing the push button the operator can effect incremental advances of the traversing mechanism until the final desired value of the component being trimmed is achieved.

A foot switch is depressed to initiate the trim cycle, and it is held in depressed position while the push button is used to make incremental advances. When the foot switch is released the trim cycle is terminated and the apparatus returns to starting position.

By addition of a three-way solenoid valve to the supply line for pressurized air, the abrading unit may be stopped during such interruption and both sides of a double acting piston in the air motor are then vented to atmosphere. This action stops the traversing mechanism. Upon deenergizing the three-way solenoid valve the air motor is repressurized and traversing may continue without returning to start position. At any time during the trim cycle, whether or not the trimming operation is being interrupted, the operation may be terminated and the nozzle returned to start position by removing pressure from the foot switch.

DESCRIPTION OF THE DRAWING

The single FIGURE of the drawing is a diagrammatic view of abrading apparatus embodying the invention.

DESCRIPTION OF THE PREFERRED EMBODIMENT

The illustrated abrading apparatus will now be described as to the trimming of a thick-film resistor, electrical element, or other workpiece designated generally by the numeral 10, utilizing a high velocity abrasive stream issuing from a nozzle 12. The latter is supplied through a supply tube 14 by a mixing chamber 16 where dry, filtered, pressurized air at about 85 p.s.i. from a compressor 18 is uniformly mixed in the desired proportions with abrasive powder from a reservoir 20.

By means of an arrangement more fully described in U.S. Pat. No. 3,344,524, a vibrator 22 is employed to apply vibrations to the chamber 16. This arrangement can produce a trickle of about 3 to 5 grams per minute of aluminum oxide or other abrasive powder having an average particle size of 27 microns, from the reservoir 20 through a passageway (not shown) to the mixing chamber 16 for combining with pressurized air.

The flow of airborne abrasive particles is initiated by the energization of a solenoid operated valve 24 in the upstream end of the supply tube 14, that is, at the outlet of the mixing chamber 16. The nozzle 12 will have a restricted orifice, e.g. 0.018 inch diameter, of much smaller cross-sectional flow area than the supply tube 14. In order to achieve uniform cutting action the apparatus is arranged to provide a uniform concentration of particles in a constant airstream issuing from the nozzle at about 40 to 80 p.s.i.

Valve 24 may be a solenoid operated pinch valve. The supply tube 14 may be a flexible hose of abrasion resistant material at the end of a length of rigid tubing, and it is preferred that the terminal or end portion adjacent the nozzle 12 be of rigid tubular construction so that it can serve as nozzle holder 26 capable of having its movements accurately controlled by a traversing mechanism 28 connected thereto by a rigidly constructed arm 30. The nozzle holder 26 is suitably journaled in the extended free end of the arm 30, in upright position above a holder 32 for the workpiece 10. Further details of construction of the traversing mechanism 28 appear herein and it is noted here that the mechanism 28 serves to move the nozzle 12 by its holder 26 transverse to the longitudinal extent of the holder, whereby the abrasive stream is traversed along the length of the workpiece to cut or abrade along the line of travel.

The traversing mechanism 28 responds to controlled flow of pressurized air through conduits 34 and 35, commanded by a control 36, to move a controlled distance first in one direction and then in opposite or reverse direction upon completion of an abrading operation. The control 36 also sends energizing current through conductors 38 to the solenoid of valve 24 to effect its closing upon completion of an abrading operation; but otherwise during abrasive trimming the valve 24 is held open.

The workpiece 10 may be an electrical resistor having a thick, electrically resistive film printed on a correspondingly shaped substrate, as more fully described in U.S. Pat. No. 3,589,081.

The traversing mechanism 28 is shown as an air motor having a cylinder 40 containing a double acting piston 42 secured to the arm 30. The inner end of the arm 30 acts as a piston rod and carries thereon pistons 44 and 46 of a variable hydraulic damper system.

Hydraulic fluid is contained in the damper system, including chambers 48 and 50 within the cylinder, as well as loop line 52 and bypass line 54. As the arm 30 moves leftward, fluid in chamber 48 is displaced clockwise through bypass line 54 to chamber 50 at a rate permitted by a flow regulating valve 56 in bypass line 54. Fluid is prevented from flowing clockwise through loop line 52 by check valve 58. However, when the arm 30 moves rightward and creates a region of reduced pressure in chamber 48 fluid returns thereto via loop line 52. By this arrangement the speed of nozzle 12 travel during trimming of a workpiece 10 is regulated

by the damper system in accordance with the setting of valve 56.

The arm 30 is driven leftward when pressurized air is introduced via conduit 35 to chamber 60, while chamber 62 is simultaneously vented to atmosphere via conduit 34. The pressure differential on opposite sides or faces of piston 42 effects movement in the direction of the side of lower pressure. Accordingly, the arm 30 is reversed or moved rightward by venting chamber 60 to atmosphere through conduit 35 while pressurizing chamber 62 through conduit 34.

Pressurization and venting of the chambers 60 and 62 is effected by a four-way solenoid valve 64. In the deenergized position, as shown, solenoid valve 64 connects conduit 34 to a supply line 66 for pressurized air. Line 66 is connected through a main air supply line 68 to the air compressor 18. Also while deenergized, solenoid valve 64 connects conduit 35 to atmosphere through a vent tube 70. When solenoid valve 64 is energized the connections are reversed; and conduit 35 is connected to supply line 66, while conduit 34 is connected through vent tube 70 to atmosphere.

Main air supply line 68 feeds pressurized air in parallel to supply tube 14 and supply line 66 from compressor 18 so long as solenoid valve 72 in line 68 is energized. Solenoid valve 72 is normally closed, but it opens when energized directly from main electrical conductors L1 and L2 upon closing main switch 74.

Closing main switch 74 also connects foot switch 76 to L1. In normal position, as shown, foot switch is held by a spring force with its blade against contact 78, thereby energizing solenoid valve 24 through conductors 38 and closing supply tube 14 to flow of any abrasive stream. It is to be noted that in the illustrated position of foot switch 76 the vibrator 22 and the solenoid valve 64 are deenergized. Therefore, when the main switch 74 is closed and the foot switch 76 is not yet depressed, the delivery of air to mechanism 28 retracts the arm 30 and nozzle 12 rightward and holds them in this starting and ending position of a trim cycle.

Depressing foot switch 76 brings its blade into engagement with contact 80 after disengagement with contact 78. With switch 74 closed this action deenergizes solenoid valve 24 and opens tube 14 to flow, while energizing solenoid valve 64 through conductor 82 to initiate leftward motion of the nozzle 12. At the same time vibrator 22 is energized through the normally closed contacts 84 of gang switch 86. Thus, depressing foot switch 76 initiates the trimming operation and with the illustrated apparatus trimming may continue until pressure on the foot switch is released.

Various well known automatic control devices are available for interrupting a trim cycle. These may be used with the apparatus described herein, but a description thereof is omitted for the sake of brevity.

Gang switch 86 includes normally open contacts 88 between L1 and conductors 38 to solenoid 24, also normally open contacts 90 between contact 80 of foot switch 76 and three-way solenoid valve 92 in conduit 35. Gang switch 86 is a push button switch held positioned as shown by a spring or other suitable biasing force. When switch 86 is depressed its blades will bridge and close contacts 88, also contacts 90 respectively; and another blade will disengage contacts 84.

Gang switch 86, together with solenoid valve 92, provides a convenient means for manually interrupting and continuing the trimming cycle while the foot switch 76

is depressed, its blade engaging contact 80. By pushing and releasing the push button of gang switch 86 it is possible to effect very small incremental movements of the nozzle. Flow of the abrasive stream is interrupted while the traversing mechanism 28 is halted; and flow resumes when traversing movement continues. With this arrangement more precise manual trimming is possible.

When solenoid valve 92 is deenergized, conduit 35 is open for flow in either direction, and it is closed to a vent 94 leading to atmosphere. Thus, with foot switch 76 not depressed, chamber 60 is vented to atmosphere through conduit 35, deenergized valves 92 and 64, and vent 70; and, with foot switch 76 depressed, chamber 60 is pressurized from line 66 through energized solenoid valve 64, deenergized solenoid valve 92, and conduit 35.

Solenoid valve 92 can only be energized through the contacts 90 of gang switch 86 when the foot switch 76 is depressed and its blade engages contact 80. When the circuit is thus conditioned a trim cycle is in progress, with pressurized air flowing through conduit 35 toward chamber 60. Upon pressing the push button, gang switch closes contacts 90 to energize solenoid valve 92. As a result, conduit 35 is blocked and chamber 60 is vented to atmosphere through vent 94. With chamber 62 also vented to atmosphere through valve 64 and vent 70, piston 42 is unpressurized and is at a standstill. Gang switch 86 simultaneously opens contacts 84 and deenergizes the vibrator 22, plus closes contacts 88 to energize solenoid valve 24 and close the supply tube 14.

With the present invention provision is made for interrupting a trim cycle to effect precise trimming under manual control by the simple and inexpensive addition of three-way solenoid valve 92 and gange switch 86.

The invention may be applied to apparatus for trimming capacitors and other electrical elements, as well as for trimming resistors.

The solenoid valves 24, 64, 72 and 92 are shown in de-energized position, each with a tension spring which is stretched when its associated field coil is energized and which therefore biases the valve to de-energized position when it is in energized position.

We claim:

1. In apparatus for adjusting the electrical value of an electrical element by abrasion, including a pressurized air supply, an abrasive powder supply, a device connected to said air supply and said powder supply for mixing pressurized air and abrasive powder to provide a stream of airborne abrasive powder, a nozzle for directing said stream at an electrical element undergoing adjustment of its electrical value, a tube connecting said nozzle to said device for delivering said stream to said nozzle, a traversing mechanism including an air motor powered by pressurized air for moving said nozzle along said electrical element first in one direction during adjustment of electrical value and then in reverse direction to start position after adjustment of electrical value, and a first control for controlling the flow of pressurized air to said air motor for effecting movement of said nozzle in one direction and in reverse direction, that improvement comprising a second control for interrupting the flow of pressurized air to said air motor during movement of said nozzle in one direction.

2. Apparatus as described in claim 1 wherein said first control and second control are electrically operated solenoid valves.

3. Apparatus as described in claim 2 wherein said first control includes means, operable when said first control is actuated, for effecting movement of said nozzle in one direction and for simultaneously conditioning said second control for operation, and wherein said first control further includes means for effecting movement of said nozzle in reverse direction and for simultaneously deconditioning said second control for operation when said first control is deactuated.

4. Apparatus as described in claim 2 wherein said first control is a four-way solenoid valve which in first position connects said air motor to said air supply and to atmosphere for moving said nozzle in one direction, and which in second position reverses the connection of said air motor in first position to said air supply and to atmosphere for moving said nozzle in reverse direction.

5. Apparatus as described in claim 4 wherein said second control is a three-way solenoid valve which when energized with said first control in first position blocks the flow of pressurized air to said air motor from said air supply and vents the connection of said air motor to said air supply established in first position of said first control, whereby said air motor is halted without moving said nozzle in reverse direction.

6. Apparatus as described in claim 5 wherein said

second control includes means operable in deenergized position of said second control for conducting the flow of pressurized air between said air motor and said first control in the first position of said first control and operable for conducting air vented from said air motor to atmosphere in second position of said first control.

7. Apparatus as described in claim 2 wherein said device is electrically operated, further including a push button gang switch which in first position deenergizes said device and energizes said second control, and which in second position energizes said device and deenergizes said second control, said gang switch including means biasing it to first position.

8. Apparatus as described in claim 7 having a third control comprising a solenoid valve in said tube which is normally open in deenergized position thereof, said gang switch in first position energizing said third control to close said tube and in second position deenergizing said third control to open said tube.

9. Apparatus as described in claim 1, said air motor comprising a cylinder, a double acting piston movable in said cylinder and connected to said nozzle for reciprocating movement therewith in said one direction and reverse direction, said piston being driven in said one direction by introducing pressurized air to said cylinder on one side of said piston and by venting the other side of said piston.
